DEVICE FOR ROUGHENING ROLL SURFACES

George H. Frank, Chicago, Ill., assignor to Western Electric Company, Incorporated, New York, N. Y., a corporation of New York

Application December 11, 1935, Serial No. 53,941

1 Claim. (Cl. 80—16)

This invention relates to a device for roughening roll surfaces, and more particularly to a device for roughening the surfaces of rolling mill rolls.

5 In commercial rolling mills, the material is usually moved through the successive passes between the reducing rolls entirely by frictional engagement of the rolls with the material. In some instances, particularly after a rolling mill 10 has been used for rolling rods or bars of bronze or other relatively hard materials which tend to smooth the roll surfaces, the rod engaging surfaces of the rolls become so smooth that at certain of the passes the rolls fail to instantly bite the incoming end of the rod or bar or, due to insufficient friction, the rolls fail to continuously advance the bar after it has entered the pass. This is obviously objectionable and has been overcome, heretofore, in some instances, by applying gritty matter to the surfaces of the rolls or to the surfaces of the materials being rolled. This practice is not entirely satisfactory because the presence of the gritty matter in the finished product is usually undesirable.

25 An object of the present invention is to provide an inexpensive device for roughening roll surfaces.

In accordance with one embodiment of the invention, the material engaging surfaces of rolling mill rolls are roughened by passing between cooperating rolls under pressure a roughening bar of a cross section approximating the particular reducing pass and having a series of transverse hardened teeth or ridges on one or more 35 surfaces thereof.

A more complete understanding of the invention will be had from the following detailed description when read in conjunction with the accompanying drawing, in which

40 Fig. 1 is a fragmentary elevational view of a pair of rolling mill rolls showing one of the reducing passes;

Fig. 2 is a view similar to Fig. 1, but with the surfaces of the reducing pass roughened by the method and device of the present invention;

45 Fig. 3 is an enlarged fragmentary vertical section of the cooperating rolls, with the roughening bar shown partially passed therebetween, and

Fig. 4 is a perspective view of the roughening 50 bar.

Referring to the drawing, there is shown in Figs. 1, 2 and 3 portions of a pair of cooperating rolls 10 and 11 of a conventional rod rolling mill. Such rolls are usually provided with a series of 55 peripheral grooves which cooperate to form a

series of reducing passes through which the rod to be rolled is passed in succession. One such pass is shown at 12 (Figs. 1 and 2) and comprises cooperating peripheral grooves 13 and 14 in the rolls 10 and 11, respectively.

The rolls are usually positively driven and the rod or bar is seized by the rolls at the successive reducing passes and moved therethrough solely by the frictional engagement of the depressed surfaces of the roll grooves with the rod.

10 After rolling mill rolls have been in use for sometime, the surfaces of the reducing passes sometimes become so smooth that slippage occurs between the rolls and the rod being rolled. Consequently the rolls fail to instantly bite the 15 incoming end of the rod and/or fail to continuously advance the rod after it has entered a reducing pass. It has been found that this occurs more frequently when rolling bronze or other relatively hard materials which tend to smooth the 20 roll surfaces.

The present invention affords an inexpensive method of and means for expeditiously overcoming the difficulties above referred to without interfering appreciably with the continuous 25 operation of the rolling mill. Thus, in accordance with this invention, when the roll surfaces at any of the reducing passes become too smooth to properly bite and advance the incoming rod, the rod engaging surfaces of the rolls at these 30 passes are quickly re-roughened without removing or displacing the rolls by passing therethrough a bar having a hardened rough surface. Preferably, the roughening bar is of a cross section approximating the shape of the particular 35 pass the surfaces of which are to be roughened.

In Fig. 4 of the drawing, there is illustrated a roughening bar 15 designed to be used at a reducing pass such as illustrated at 12 in Fig. 1. The bar 15 is provided with a series of hardened 40 transverse teeth or ridges 16 on opposite sides thereof. When the bar is passed between the rolls as shown in Fig. 3, the teeth 16 penetrate the depressed surfaces of the grooves 13 and 14, thereby forming therein spaced apart indentations 18 (Figs. 2 and 3) which roughen the surfaces sufficiently to again function properly.

45 It will be understood that the rough surfaces of the roughening bar may be of any desired configuration and that a corresponding rough surface will be imparted thereby to the roll surfaces. Also, the roughening bar should be of such cross-sectional dimensions that when passed between the rolls, the hardened rough surfaces of the bar 50 will be pressed against the roll surfaces with suffi- 55

cient force to produce indentations in the roll surfaces. For reducing passes comprised by V-shaped peripheral grooves in the rolls, the roughening bar may have rough surfaces on all four sides so that both sides of the V-grooves are roughened.

10 In order to prevent cracking or breaking of the roughening bar while being passed between the rolls, only the rough surfaces thereof are hardened, the interior thereof being relatively soft.

15 It should be understood that the invention is not limited to the specific embodiments thereof herein illustrated and described except insofar as is defined by the appended claim.

What is claimed is:

A device for roughening working surfaces of rolling mill rolls comprising a substantially straight bar of substantially uniform cross section throughout its length adapted to be inserted 5 and completely passed lengthwise between cooperating rolling mill rolls by the rotation of one of the rolls while said rolls are in their working positions, said bar having a hard outer surface and a relatively soft interior, and a series of trans- 10 verse cutting teeth on said outer surface adapted to contact with and roughen the working surface of one of the rolls while said bar is passed between said rolls.
